TIME-CONTROLLED DEVICE FOR SWITCHES
AND THE LIKEBevan Graham Horstmann, Bath, Somerset,
EnglandApplication December 3, 1938, Serial No. 243,848
In Great Britain May 20, 1938

12 Claims. (Cl. 200—38)

This invention relates to time controlled devices of the kind in which a member to be controlled such as an electric switch or gas valve can be moved into one position (e. g. "on") and held in that position for a predetermined operative time interval—which is usually adjustable—at the expiration of which the switch or the like is moved automatically to another position (e. g. "off"). Time controlled devices of this nature are often associated with electric switches or gas valves whereby the electric or gas supply may be brought into use for present periods as desired, a particular application being to electric or gas cooking appliances to enable a required cooking period to be placed under the control of the device so as to be terminated automatically at the selected time. In this kind of device a timepiece drives an adjustable actuating device for the switch or valve which sometimes takes the form of tappets or levers adjustable in relation to a time-graduated driven dial, or which may be any other suitable device capable of setting in relation to the timepiece drive to bring the controlled switch or valve into and out of operation at pre-arranged times. Such an actuating device, for convenience, is referred to herein as the "period" member, controlling as it does the commencement and cessation of the operative period of the switch, valve or other element under control.

The object of the present invention is to provide a time controlled device of the above described kind in which the pre-set operative time period can be caused to commence functioning either at the time of setting the period member, or at any selected time thereafter by setting an auxiliary member termed herein a "delay member" which is also timepiece driven, and adjustable to set a pre-arranged time period to delay the commencement of the actual operative period. Thus in the application of the device to an electric or gas cooking appliance, the cooking period—the length of which can be pre-set as desired by the period member—may be delayed so as to come into operation as and when may be required.

According to this invention there is provided time controlled mechanism applicable to electric switches, gas valves or other devices to be controlled, comprising a timepiece, a period member adjustable to pre-set an operative time period for the device to be controlled and adapted to be driven by the timepiece through a coupling, a delay member also adapted to be driven by the timepiece and manually adjustable to pre-set a

time delay interval and at the setting simultaneously to uncouple the drive between the timepiece and period member, and means whereby the delay member automatically re-couples the period member drive at the termination of the delay interval to start the drive of the period member and commence the pre-set operative time period.

Some practical embodiments of the invention will be described by way of example as applied to the control of an electric switching device particularly intended for use with an electric cooker, these embodiments being illustrated in the accompanying drawings wherein:

Figure 1 is a front elevation of one embodiment;

Figure 2 is a section on the line II—II of Figure 1;

Figure 3 is a detail view of the switching arrangement;

Figure 4 is front elevation of the second embodiment;

Figure 5 is a section on the line V—V of Figure 4;

Figure 6 an elevational view with dials removed to show the switch actuating mechanism of the embodiments of Figures 4 and 5;

Figure 7 is a side elevation looking from the left hand side of Figure 4, and serves primarily to show the relative disposition of the switch actuating part;

Figure 8 is a front elevation of the third embodiment;

Figure 9 is a section on the line IX—IX of Figure 8; and

Figure 10 is a diagram of the switching arrangement in the synchronous motor and heater circuits.

Referring to the first embodiment the adjustable period mechanism consists of a control knob 1 which is axially displaceable on but rotatable with a spindle 2 which is rotated by a synchronous motor driven clock movement generally designated 3. Behind the control knob 1 and surrounding the spindle 2 are two dials, the outer dial 4 being referred to hereinafter as the pre-set time period or cook dial and the second as the delay dial 5. The control knob 1 drives the delay dial 5 by means of a primary pin 6 on the latter projecting through an arcuate slot 7 in the cook dial into a socket 8 in the control knob, whilst a releasable driving connection to the cook dial 4 is provided by pins 9 on the hub of the cook dial which engage in sockets carried by the control knob.

The cook dial is permitted a maximum movement in one direction—say clockwise, this movement corresponding to the longest cooking period provided, and to switch on the device, the control knob 1 is turned by hand in this direction to the maximum permitted extent, carrying with it both dials 4 and 5. The result of this movement is to close the synchronous motor and heater circuits, after which the control knob with the dials 5 is turned back through a distance which subtracted from the maximum permitted movement leaves a complementary distance corresponding to the predetermined operative time period required. Under the action of the synchronous 10 motor clock movement, the knob and the dials will continue to rotate backwards until this complementary distance has been taken up—which means the termination of the operative time period—and the knob or cook dial is provided 15 with means such as a pin which then opens the switches controlling the synchronous motor and heater circuits.

As above described the required operative time period i. e. cooking period starts as soon 20 as the cook dial 4 has been set. To delay the commencement of this time period, the two dials 4 and 5 are set as before by means of the control knob 1, and the latter is then pulled axially away from the dials against the action of a spring 10 enclosed within the control knob and abutting the head of the driving spindle 2. This 25 axial displacement of the control knob releases the driving pins 9 on the cook dial 4 from the sockets on the control knob, but the primary pin 6 of the delay dial, which is longer than the pins 9, remains in engagement with the control knob so that the delay dial can now be turned forward by hand without affecting the setting of the cook dial. It will be observed that the cook dial 4 30 is mounted on a fixed sleeve-like boss 11 in the enclosing casing 12, with the outer portion of a friction ring 13 which, whilst it permits setting of the cook dial and the driving thereof by the synchronous motor when the two dials are coupled together nevertheless, serves to retain the 35 cook dial in adjusted position during setting and return of the delay dial. Further it will be observed that when the delay dial 5 is uncoupled from the cook dial, it can rotate freely on the hub 14 of the cook dial.

The distance the delay dial 5 is turned forward to displace the two dials angularly as above described, will depend on the time interval which is required to take place before the operative pre-set time period set on the cook dial 4 begins to function. During the delay period the control knob 1 and the delay dial 5 will be rotated backward by the synchronous motor movement, but the cook dial 4 will remain stationary until the driving pins 9 on the hub 14 register with the corresponding sockets of the control knob, the control knob then moving axially inwards under the action of the spring 10 thereby to lock the cook dial 4 to rotate with the control knob 1 and delay dial 5 so that the predetermined operative time period commences. In Figure 10, the circuit connections for the heater 15 and the synchronous motor 3 are shown schematically. In this circuit arrangement, the synchronous motor circuit includes the supply leads 16 and a primary switch 17 which normally i. e. in the zero position of the two dials is open, whilst the circuit for the heater 15 includes the supply leads 16, the primary switch 17 and a secondary switch 18 which is normally closed. Consequent upon

setting of the cook dial 4, the primary switch 17 is closed thus establishing the synchronous motor and heater circuits, and this switch will only open again at the end of the pre-set operative time period when the two dials have returned 5 to their zero position. When the delay dial is set, however, it causes the heater circuit to be broken at the switch 18, which circuit is re-established as soon as the control knob 1 moves inwards to commence the predetermined operative time period. For this purpose the normally closed contacts of the switch 18 are controlled by a member which is carried by the knob 1 and adapted to open the contacts as the knob is displaced axially outwards and to close them again 15 as the knob moves inwards. A suitable construction for effecting this operation is shown in the embodiment illustrated in Figures 4 to 7, and may be applied here.

Suitable time scales 19 and 20 may be provided 20 on the two dials 4 and 5, which move past a window 21 in the casing 12 of the device, the scale 19 on the cook dial 4 being set in relation to the left hand edge 22 of the window 21 and the delay dial scale 20 in relation to the edge 23 25 of the cook dial 4.

In the drawings, the mechanism is shown adjusted to give an operative time period of three hours, and a delay period of one hour as will be seen from an inspection of Figure 1. 30

Any suitable form of switching arrangement may be incorporated in the device, but a convenient and simple form is that illustrated in the accompanying drawings. Thus for actuating switch contacts of the switches 17 and 18 in the synchronous motor and heater circuits, there is provided a one-armed actuating lever 24 which is pivoted at 25 to the inner wall of the casing 26 for the switch contacts, and which carries at its free end a roller 27 adapted to ride on the periphery of a cam plate 28 under the action of spring pressing on the actuating lever. For this purpose the inherent resilience of the contacts of the primary switch 17 is utilised, the latter being mounted horizontally under the actuating 40 lever, so that the upper movable contact 17a in the normally open position, presses the lever 24 upwardly. The cam plate 28 is fixed to rotate with the cook dial 4, and at a point disposed at the end of the permitted movement of the 45 latter, it has a rise 29 which moves the actuating lever 24 outwardly to close the contacts of the switch 17. Simultaneously a pin 30 on the cook dial 4 moves forward a locking cam ring 31 loose about the axis of the spindle 2 into engagement with the roller 27 which eventually at the conclusion of the forward movement, seats in a recess 32 in the loose ring, so that the actuating 50 lever 24 is locked in the operative position. The cook dial can now be moved back to set the required operative time period without the contacts of switch 17 being affected. When this period expires, a pin 33 on the cook dial 40 displaces the loose ring 31 from the roller 27 thereby releasing the actuating lever 24 so that the contacts of switch 17 open.

In the detail Figure 3, the contacts of switches 17 and 18 are shown in the operated positions that is to say, switch 17 is closed and switch 18 open, as occurs when the device has been set to 70 provide for a delay period before commencing the operative time period.

In the embodiment illustrated in Figures 4 to 7, the cook dial 44 is disposed behind the delay dial 45 which is formed integral with the control knob 75

41, and which, after setting, is driven backwards by the synchronous motor movement 43 through gears 46 and 47 of which gear 46 is fixed to a sleeve 48 rotatable and axially displaceable on the spindle 42 and rigid with the control knob, the latter being pressed inwardly by a spring 50 and the width of the gear 47 being such that in any axial position of the control knob the gear 46 is always engaged therewith. The cook dial is coupled to the delay dial through a projection 49 on the back of the delay dial which normally engages in a corresponding socket 49a in the cook dial. This coupling enables the cook dial to be set to a desired operative time period by manipulation of the control knob, and then both dials to be driven backward by the synchronous motor, providing no delay has been set. Axial displacement and angular adjustment of the delay dial to set a particular delay period, however, releases the coupling by disengaging the projection 49 from the socket and causing the same to run on the face of the cook dial. At the termination of the delay period during backward rotation of the delay dial by the synchronous motor, the projection drops into the cook dial socket 49a under the action of the spring 50, whereupon the two dials are re-coupled and rotate together through the angular distance corresponding to the pre-set operative time period until zero position is reached, at which position the primary switch 17 is opened so that not only the heater circuit but also the synchronous motor is disconnected. The drive to the two dials therefore stops.

On and extending angularly about the head of the casing 43, is a fixed cook period scale 51, and the cook dial is set in relation to this scale by providing it with an annular peripherial portion 52 which embraces the delay dial and which has a time mark 53 moving adjacent the fixed cook period scale. The delay dial is set in relation to the cook dial, being provided with a scale 54 which moves adjacent the time mark 53 on the cook dial.

The switching arrangement controlled by the two dials is arranged—as in the previous embodiment—so that the cook dial has to be turned clockwise the angular amount corresponding to the greatest cooking period allowed and then turned back to the point which leaves a complementary distance corresponding to the desired operative time period. If the commencement of this period is to be delayed, the delay dial is pulled axially outwards and adjusted a further amount from zero, the adjustment being in the same direction, namely clockwise, as the setting of the cook dial until the desired indication on the delay scale registered with the time mark 53, the resulting angular spacing of the two dials having to be taken up before the operative period comes into operation.

When the cook dial is moved through the maximum permitted angular distance, a pin 55 projecting from the back of the cook dial 44 and running in an arcuate slot 56 in the casing 43—which slot determines the said permitted movement—engages near the end of its travel a projection 57 on the end of one arm of a two-armed actuating lever 58. The lever 58 swings about a pivot 59 and carries on the end of its other arm 60 an insulated roller 61 which co-operates with the contacts of the primary switch 17. The pin 55 upon engaging the projection of the lever 58, rocks the latter against the action of a spring 62 so that its switch actuating arm 60 turns anti-clockwise to cause the roller 61 to close the contacts of the switch 17 as shown in the drawings. The switch actuating lever is locked in this position by means of a shelf 63 thereon which catches over a ledge 64 on a locking lever 65, controlled by a spring 66. The cook dial can thus be set back to the required operative time period without affecting the operated condition of the primary switch contacts.

During the operative time period the pin 55 travels back with the cook dial in anti-clockwise direction, and at the termination of the period when it is near the bottom end of the arcuate slot 56, it engages a lug 67 on the end of the locking lever 65, thereby depressing the latter downwardly to remove the ledge 64 from the shelf 15 on the actuating lever 58, which thereupon is utilized to rock under the action of its spring 61 in a direction to depress the switch actuating arm 60 and remove the roller 61 from the switch contacts; which thus open. This switching "off" takes place when the time mark 53 reaches the zero mark on the cook period scale 51. To ensure that switching "off" takes place, should the release of the locking lever fail to achieve the desired result, the switch actuating arm 60 has an upward extension 68 which lies in the path of the pin 55 so as to be engaged thereby at the end of the operative time period, with the result that the switch actuating arm is depressed positively.

For opening the secondary switch contacts in the heater circuit when the start of the operative time is to be delayed, the movable contact of the switch 18 has a tongue piece which engages in an annular recess 68a in the back of a hub portion of the delay dial 45 whereby when the latter is pulled axially outwards to release the aforesaid coupling previous to setting the delay period, the movable contact is moved away from the opposite contact, as will be seen from Figure 5, thus opening the switch.

To retain the cook dial in set position during setting and throughout the duration of a delay period, a friction brake 69 is interposed between the cook dial and its mounting.

In the further embodiment of the invention disclosed in Figures 8 and 9, the delay dial 75 has a control knob 71 and is secured to a spindle 70 which is formed at its inner end with an interiorly screw threaded socket 72 which screws on to an exteriorly threaded spigot 78 fixed to the casing of the synchronous motor movement generally designated 73. The inner end of the delay dial spindle carries a pinion 76 which permanently meshes with a pinion 77 of the synchronous motor movement irrespective of the axial position of the delay dial. The member by which the cooking period is set comprises a knob 74 which is secured to the periphery of an inner disc 79 mounted on a fixed sleeve 80 with the interposition of a friction brake band 81. The normally open contacts of the primary switch 17 are disposed to one side of the delay dial and the movable contact is provided with an extension 82 which lies in the path of an insulated pin 83 projecting from the back of the disc 79. When the cook knob 74 is moved clockwise over the fixed scale 74a to pre-set an operative time period, the pin 83 moves away from the contact extension 82 so that the switch 17 closes to establish the synchronous motor and heater circuits.

In this embodiment the normally closed contacts 84 of the secondary switch 18 which controls the heater circuit are carried the one by the delay dial and the other by the disc 79 to which the cook knob 74 is secured. For this purpose the 75

delay dial spindle 70 is provided with a radial arm 85 to the end of which one of the contacts 84 is secured whilst the other contact is carried by a projection 86 from the back of the disc 79. 5 Brushes 87 and 88 are electrically connected respectively to one of the contacts 84 and wipe over arcuate conductors 89 and 90 which are brought out to the terminal block 91 supporting the contacts of primary switch 17, and which are 10 connected in the heater circuit. The contact carried by the arm 85 is in advance of the contact carried by the projection on the disc 79, and it will be seen therefore, that as the cook knob 74 is set to a desired cooking period, the disc 79 will 15 turn the delay dial through mechanical coupling provided by the contacts, the heater circuit being maintained through the arcuate conductors 89 and 90. If no delay period is required, the synchronous motor in rotating the delay dial backward 20 via the gearing 76 and 77 will also drive the disc 79 and thereby the cook knob 74 backward through the mechanical coupling provided by the engaging contacts 84. If a delay period is 25 desired, the delay dial, following the setting of the cooking period, will be turned manually through a further angular distance corresponding to the delay period required, which results in the breaking of the aforesaid coupling since the contact carried by the arm 85 moves away from the 30 contact carried by the projection 86, and the heater circuit is thereby also opened. The delay dial is provided with scale 92 by which the setting of delay period may be effected by turning the delay dial until the delay period indication on its 35 scale registers with a pointer 93 on the cook knob 74. At the termination of the delay period the contacts 84 will re-engage thus re-establishing the heater circuit as well as the mechanical coupling through which the drive to the cook knob 40 is effected.

It will be observed that during rotation of the delay dial, the spindle 70 of the latter works up and down on the screwed spigot 78, the axial movement producing a wiping action of the contacts 84.

In each of the embodiments described herein there will be provided in the drive from the synchronous motor to the delay dial, a free wheel clutch (not shown) which permits the setting of 45 the period and delay members to be effected freely without movement of the synchronous motor.

Although dials have been referred to herein they may be pointers or other suitably shaped members for enabling the required setting to be 50 done.

I claim:

1. Time controlled mechanism applicable to 55 electric switches and the like to be controlled, comprising a timepiece, a period member adjustable to pre-set an operative time period for the device to be controlled and adapted to be driven by the timepiece through a coupling, a delay member also adapted to be driven by the timepiece and manually adjustable to pre-set a time 60 delay interval and at the setting simultaneously to uncouple the drive between the timepiece and period member, and means whereby the delay member automatically re-couples the period member drive at the termination of the delay interval to start the drive of the period member and commence the pre-set operative time period.

2. Time controlled mechanism according to 65 claim 1, in which the period member is adjustable in one direction to pre-set an operative time

timepiece drives the adjusted period member in the direction opposite to its setting, the delay member being adjustable to render the timepiece drive to the period member ineffective for a pre-determined delay interval. 5

3. Time controlled mechanism applicable to electric switches and the like to be controlled, comprising in combination period and delay members connected together through a releasable coupling by which both members can be manually adjusted together in one direction from zero position for setting a time period, and the delay member then uncoupled to enable it to be further adjusted in the same direction independent of the period member, a timepiece connected to 10 drive the delay member in the opposite direction back to its zero position, and to drive the period member in the same direction when coupled to the delay member, means whereby when the period member is uncoupled, re-coupling 15 thereof is effected at the end of a delay interval determined by the extent of the independent adjustment of the delay member, and actuating means connecting the two members to the device to be controlled so that the adjustment of 20 the period member pre-sets an operative time period for the said device, the independent adjustment and uncoupling of the delay member rendering such pre-setting ineffective until the expiry of the set delay interval. 25

4. Time controlled mechanism according to 30 claim 3, wherein the period and delay members are coaxially mounted and adjustable angularly.

5. Time controlled mechanism according to 35 claim 3 wherein the period and delay members are co-axially mounted and wherein the delay member is axially adjustable to effect release of the coupling between the two members when a delay period is to be set.

6. Time controlled mechanism according to 40 claim 3 wherein the period and delay members are coaxially mounted and are adjustable angularly, the delay member being axially adjustable to effect release of the coupling between the two members when a delay period is to be set and 45 wherein the coupling comprises a dog on one member engaging in a corresponding socket on the other member, there being a spring normally maintaining the coupling parts in engagement.

7. Time controlled mechanism according to 50 claim 3 wherein the period and delay members are coaxially mounted and wherein the coupling between the two members comprises complementary parts one angularly in advance of the other so that setting of the period member turns the delay member, and backward driving of the delay member by the timepiece turns the period member backward. 55

8. Time controlled mechanism according to 60 claim 3 wherein the period and delay members are provided with time scales and marks adapted to be set one against the other and in relation to a fixed scale or mark to effect the desired pre-setting of the operative time and delay periods.

9. Time controlled mechanism according to 65 claim 3, wherein the timepiece is a synchronous electric motor and the period member controls a primary electric switch connected in the circuit of the motor, whilst the delay member co-operates with a second electric switch connected in 70 a heater or other circuit which also includes the primary switch, the arrangement being such that the primary switch is normally open and is closed by the setting of the period member, and the

opened when the delay member is adjusted for a pre-determined delay period.

10. Time controlled mechanism according to claim 3, wherein the timepiece is a synchronous electric motor and the period member controls a primary electric switch for the motor while the delay member controls an operating circuit including the primary switch, wherein means for actuating the two switches comprises a lever which is depressed and locked by the setting of the period member to effect operation of the primary switch, and a member which is displaced by axial movement of the delay member to open the primary switch.

11. Time controlled mechanism according to claim 3 wherein the coupling between the two

members comprises complementary parts one angularly in advance of the other so that setting of the period member turns the delay member, and backward driving of the delay member by the timepiece turns the period member backward, the period and delay members being coaxially mounted and adjustable angularly, and wherein the complementary coupling parts carry the contacts of the secondary switch which are electrically connected to brushes wiping over arcuate 10 conductors.

12. Time controlled mechanism according to claim 3, wherein braking means are provided for maintaining the period member in set position during setting and return of the delay member. 15

BEVAN GRAHAM HORSTMANN.
